GLOVE

Herman Kress, New York, N. Y.

Application January 19, 1951, Serial No. 13,877

Term of patent 3½ years

(Cl. D3—11)

To all whom it may concern:

Be it known, that I, Herman Kress, a citizen of the United States and a resident of the city, county and State of New York, have invented a new, original, and ornamental design for a glove, of which the following is a specification, reference being had to the accompanying drawing, forming part thereof.

In the drawing:

Fig. 1 is a front view of a glove embodying my design;

Fig. 2 is a rear view thereof; and

Fig. 3 is a fragmentary front view thereof illustrating the pocket as it appears in open position.

I claim:

The ornamental design for a glove, as shown.
HERMAN KRESS.
